A. ROGERS.
FAUCET HOUSING.
APPLICATION FILED APR. 13, 1915.

1,221,093.

Patented Apr. 3, 1917.

UNITED STATES PATENT OFFICE.

ALFRED ROGERS, OF MILTON, MASSACHUSETTS.

FAUCET-HOUSING.

1,221,093.

Specification of Letters Patent. Patented Apr. 3, 1917.

Application filed April 13, 1915. Serial No. 21,098.

To all whom it may concern:

Be it known that I, ALFRED ROGERS, a citizen of the United States, and resident of Milton, in the county of Norfolk and State 5 of Massachusetts, have invented certain new and useful Improvements in Faucet-Housings, of which the following is a specification.

The object of the present invention is to 10 provide a non-corrodible housing for a faucet and a non-corrodible handle for a faucet, whereby all the metal parts may be concealed. The housing and handle may be made of china, celluloid, or iron covered 15 with enamel. The practical advantage of the non-corrodible elements is that they dispense with the necessity of plating and polishing the metal parts which have hitherto been exposed to view.

20 The invention consists also in an improved form of connection between a china handle and the valve of a hot-water faucet, whereby the handle will be free from liability of being broken or cracked by stresses 25 due to expansion and contraction of the metal parts.

Of the accompanying drawings, which illustrate two forms in which the invention may be embodied:

30 Figure 1 represents a sectional view including a portion of a basin, a portion of a basin slab, a faucet, a faucet housing composed of non-corrodible material such as china, and a faucet handle composed of such 35 non-corrodible material.

Fig. 2 represents a bottom plan view, on a smaller scale, of the non-corrodible housing shown in Fig. 1.

Fig. 3 represents a section through the 40 structure intersected by line 3—3 of Fig. 1.

Fig. 4 represents a sectional view similar to Fig. 1, showing another form of non-corrodible housing and another form of non-corrodible handle.

45 Fig. 5 represents a bottom plan view, on a smaller scale, of the housing included in Fig. 4.

Fig. 6 represents a section through the structure intersected by line 6—6 of Fig. 4.

50 Fig. 7 represents a sectional view through the structure intersected by line 7—7 of Fig. 4.

The same reference characters indicate the same parts wherever they occur.

55 Referring first to Figs. 1 to 3, a portion of a basin is indicated at 10, and a portion of a

basin slab is indicated at 11. I have shown a well-known form of basin faucet the body portion of which is indicated at 12, and the spout of which is indicated at 13. The faucet has a tubular stem 14 through which water is conducted from a supply pipe (not shown). A flange 15 formed upon the body of the faucet is arranged to be seated upon the slab 11. A nut 16 having screw-threaded 60 engagement with the stem 14 serves to keep the flange 15 seated upon the slab and to hold the faucet in place. The slab has an opening 17 through which the stem 14 extends.

A housing or shell composed of non-corrodible material, such as china, and comprising a substantially tubular body portion 20 and a spout portion 21, is arranged to cover the body portion and spout portion of 70 the faucet. The body portion 20 is open at both ends, its base end having a flat rim 22 which is seated against the slab. The spout portion also has a flat rim, indicated at 23, which is likewise seated against the slab and 75 which, in conjunction with the rim 22, forms a continuous flat rim the major portion of which is seated against the slab, while the portion which projects beyond the slab, at the right of Fig. 1, provides an opening 80 through which water may flow from the faucet spout 13. In this form the base opening is partly in the body portion 20 and partly in the spout portion 21, and the housing is for this reason capable of being applied and removed without being tipped and 85 without disturbing the faucet. The body portion 20 tapers from its base end to its opposite end, the base end being enlarged to give clearance for the flange 15 and to give 90 the housing ample breadth of bearing upon the slab. The opposite end portion of the body portion 20 is preferably cylindric in form and is substantially smaller in diameter than the base end, both for the sake of 95 appearances and also to coöperate with the handle, as hereinafter specified, to conceal the metal parts by which the handle is connected to the faucet.

A sleeve 24 coöperates with the faucet to 105 secure the housing member in place. This sleeve has a flange 25 which projects laterally and which is seated upon the end face of the smaller end of the body portion 20. The sleeve and faucet have coacting screw-threads, indicated at 26, whereby the sleeve 110 upon being screwed on to the faucet causes

the flange 25 to bear against the shell or housing, to keep the latter seated against the slab. The sleeve is capable of turning relatively to the shell or housing, but fits the cylindric portion of the latter closely enough to center the shell or housing relatively to the faucet.

A handle composed of non-corrodible material, such as china, is indicated at 27. In the form shown by Fig. 1 the handle is formed with an annular groove 28, and with an annular rim or flange 29 which overlaps the smaller end of the body portion 20 when the faucet is closed, to conceal the metal parts which would otherwise be exposed to view between the handle and the shell or housing. The valve 30 of the faucet has a metal stem 31, and the handle 27 is fitted with a metal socket member 32 which receives the stem 31 and is detachably secured to the latter by a screw 33. The socket member 32 is permanently secured in a socket 34 in the handle, a suitable hard adhesive substance 35, such as a mixture of litharge and glycerin, being used for this purpose. The valve 30 and body portion 12 have co-operative screw-threads 36 and 37 which cause the valve to move toward and from its seat 38 in consequence of turning the handle 27.

To attach the shell or housing, the parts are assembled as follows. The faucet may first be installed in the position shown, but the sleeve 24 and handle 27 will not be attached until after the shell or housing has been applied. Assuming that the faucet is secured as shown, the shell or housing may be placed over the faucet and arranged upon the slab as shown. The sleeve 24 may then be screwed on to the faucet as far as the shell or housing will permit, the latter being thereby centered relatively to the faucet and securely held against the slab. The handle 27 may then be attached, but for this purpose the valve 30 must be unscrewed sufficiently to leave a substantial space between the rim 29 and flange 25 to enable the screw 33 to be inserted. When the handle has been attached by the screw 33 the valve may be screwed to its seat and the assemblage is then ready for use.

In the form shown by Figs. 4, 5 and 6, the non-corrodible shell or housing comprises a substantially tubular though tapering body portion 20^a and a spout portion 21^a. In each of the two forms of housing the spout portion extends laterally from the side of the body portion, but in the form shown by Fig. 4 the base portion extends beyond its junction with the spout portion. Continuing the description of the form shown by Figs. 4, 5 and 6, the body portion 20^a has a circular base rim 22^a which bears against the slab, the spout portion 21^a being offset from the rim. This style of shell or housing is formed in accordance with the faucet, which differs

from the faucet shown in Fig. 1 in that the body portion 12^a is longer and its base end projects a greater distance beyond the junction with the spout portion 13^a. In other respects the faucets are similar.

The operation of applying the housing 20^a, 21^a requires tipping in order to pass the spout portion 13^a of the faucet longitudinally through the spout portion of the housing. When applying the housing, the handle 27^a and sleeve 24^a will of course be detached, and the valve 30^a will likewise be detached to remove the stem 31^a from the necessary path of the rim 22^a. In applying the housing the latter will be moved from right to left, first passing the rim 22^a over the discharge end of the spout 13^a so that the spout will enter the base end of the tubular portion 20^a and then enter the spout portion 21^a, the body portion 20^a being carried over the body portion 12^a of the faucet and finally arranged upon the slab as shown. When the shell or housing has been arranged in the desired position, the sleeve 24^a may be applied to the faucet to secure the housing. The stem 31^a of the valve may be fastened to the handle by a screw 33^a before the valve is inserted into the faucet.

The connection between the handle 27^a and valve 30^a is specially designed for hot-water faucets, with a view to relieving the handle portion from stresses due to expansion and contraction of the metal parts. The handle, instead of having a socket such as that indicated at 34 in Fig. 1, has an angular stud portion 34^a. This stud portion is arranged in a socket formed by an angular flange 32^b formed upon a socket member 32^a. The stud 34^a is secured to the socket member by a suitable hard adhesive substance such as a mixture of litharge and glycerin. The expansion of the flange 32^b, due to the effect of hot water, does not have any tendency to split or burst the stud portion 34^a or any other portion of the handle, nor would excessive contraction of the flange 32^b result in breaking the handle, because any stress due to such contraction would be compressive, and the stud portion 34^a could well sustain compressive stress without being broken.

In the foregoing explanation of the mode of assembling the structure shown by Fig. 4, it has been assumed that the valve 30^a and handle 27^a would be connected before the valve would be screwed into the body of the faucet. Proceeding on this assumption, the remainder of the assembling operation would be as follows. The screws 40 which are shown as being threaded in the flange 25^a would be removed, or at least unscrewed sufficiently to have their inner ends flush with the internal surface of sleeve 24^a. This would enable the flange 41, which is formed upon the socket member 32^a, to

pass beyond the screws 40, and the latter would then be screwed in to the positions shown before the valve is screwed in far enough to carry the rim 29^a of the handle beyond the said screws. Having set the screws 40 in the positions shown, the valve could be screwed to its seat, thereby carrying the rim 29^a beyond the screws and into overlapping relation with the smaller end 10 of the body portion 20^a of the housing. Such metal parts as remain beyond the smaller end of the body portion 20^a occupy the annular groove 28^a in the handle and are concealed by the rim of the handle.

15 I claim:

1. The combination with a slab, and a faucet arranged in contiguous relation thereto, of a detachable faucet housing composed of non-corrodible material and comprising a body portion and a spout portion arranged to house the body portion and spout portion, respectively, of the faucet, said housing being seated against said slab.
2. The combination with a slab, and a faucet arranged in contiguous relation thereto, of a faucet housing of non-corrodible material arranged to bear against said slab and to house said faucet, said housing

having a tubular portion surrounding the valve stem of said faucet, and a handle of 30 non-corrodible material carried by said valve stem, said handle having an annular groove and said tubular portion protruding into said groove.

3. The combination with a slab, and a 35 faucet arranged in contiguous relation thereto, of a faucet housing of non-corrodible material arranged to bear against said slab and to house said faucet, said housing having a tubular portion surrounding the 40 valve stem of said faucet, and a handle of non-corrodible material carried by said valve stem, said handle having a rim overlapping said tubular portion.

4. The combination with a faucet having 45 an operating stem, of a faucet housing of non-corrodible material having an opening in which said stem is arranged, an operating handle of non-corrodible material, and means detachably connecting said handle 50 and stem, said housing and handle having coöperative lapped portions arranged to conceal said connecting means.

In testimony whereof I have affixed my signature.

ALFRED ROGERS.
